UNITED STATES PATENT OFFICE.

WILLIAM J. DUFFICY, OF DENVER, COLORADO.

SCREEN-CLAMPING DEVICE.

Original application filed July 29, 1927, Serial No. 209,340. Divided and this application filed March 12, 1928. Serial No. 261,111.

This invention relates to a clamping device for a window screen such as that forming the subject matter of an application filed by me on July 29, 1927, Serial No. 209,340, the 5 general object of this invention being to provide means for clamping the edges of the screen in its guiding grooves in the window frame to prevent movement of the screen when the same is being attached to or 10 detached from the sash.

This invention also consists in certain other features of construction and in the combination and arrangement of the several parts, to be hereinafter fully described, illustrated in 15 the accompanying drawings and specifically pointed out in the appended claim.

In describing my invention in detail, reference will be had to the accompanying drawings wherein like characters denote like or 20 corresponding parts throughout the several views, and in which:—

Figure 1 is a view partly in section of the lower half of a window, showing the invention used to clamp the edges of a screen placed 25 on a spring roller located in a chamber formed in the window frame, with means for detachably connecting the free end of the screen to a sash.

Figure 2 is a section on line 2—2 of Figure 1.

Figure 3 is a section on line 3—3 of Figure 2.

As described in the before mentioned application, a chamber 1 is formed in the window frame A and a spring roller 2 is journaled in said chamber, with one end of a screen 3 attached to the roller. The other end of the screen has attached thereto a member 4 which carries a pair of keeper eyes which are adapted to be engaged by parts of a latch rod longitudinally movable in the sash B of the window and having a handle part 5 attached to the rod which extends through a slot 6 formed in the sash so that by moving the rod by its 40 handle part 5, the screen may be attached to or detached from the sash.

In carrying out this invention, one of the strips 7 which form the guides for each side edge of the screen, is movably arranged and has an extension 8 thereon which has a hole 50 therein for receiving the crank end of a stub shaft 9 journaled in a part of the window frame with its outer end provided with a handle 10 so that by turning the shaft by means of this handle, the strip 7 is moved 55 toward and away from the other strip. When the strip 7 is moved toward the other strip, it will clamp the screen between itself and said other strip and thus hold the screen in adjusted position and against movement by 60 the spring roller.

From the foregoing it will be seen that by moving the strips 7 into clamping position, the screen will be held in adjusted position and will not be moved by the spring roller 65 when the screen is released from the sash.

It is thought from the foregoing description that the advantages and novel features of my invention will be readily apparent.

It is to be understood that I may make 70 changes in the construction and in the combination and arrangement of the several parts, provided that such changes fall within the scope of the appended claim.

What I claim is:—

Means for holding in adjusted position a screen having one end fastened to a spring roller mounted in a window frame, with the other end of the screen detachably connected with the sash, comprising guiding strips for 80 the side edges of the screen, one strip of each pair of guiding strips being movably arranged, manually operated means for moving the said strip toward and away from the other strip, such means comprising an extension on each strip having an opening therein, a crank shaft journaled in the window frame with one end engaging the opening in the extension and a handle connection with the outer end of each shaft. 85

In testimony whereof I affix my signature.

WILLIAM J. DUFFICY.
